Boston Type Foundry, No. 104 Milk Street, Boston.

UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,111, dated January 11, 1881.

Application filed November 27, 1880. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification, reference being had to the accompanying impression taken from said font.

10 The first seven types, or, more properly, logotypes, consist of the abbreviations Sun., Mon., Tue., Wed., Thu., Fri., Sat., each inclosed by horizontal straight lines above and below and vertical straight lines at each side, connecting at right angles.

15 It further consists of the types or figures 1, 2, 3, 4, 5, 6, 7, 8, 9, similarly inclosed, and

the logotypes 10, 11, 12, 13, 14, 15, 16, 17, 18, 19, 20, 21, 22, 23, 24, 25, 26, 27, 28, 29, 30, 31, also similarly inclosed. 20

It still further consists of a blank inclosure of similar lines.

These types or logotypes are intended for general use in printing, but more particularly for the composition of calendars, an impression of a calendar printed from them being submitted as an illustration. 25

I claim—

The design for types and logotypes, as described and shown.

JOHN K. ROGERS.
